UNITED STATES PATENT OFFICE.

HERMAN A. J. RIECKERT, OF NEW YORK, N. Y.

SPRING-HINGE.

SPECIFICATION forming part of Letters Patent No. 443,380, dated December 23, 1890.

Application filed February 21, 1890. Serial No. 341,270. (No model.)

To all whom it may concern:

Be it known that I, HERMAN A. J. RIECKERT, of New York city, in the county and State of New York, have invented a new and Improved Hinge, of which the following is a full, clear, and exact description.

The object of the invention is to provide a new and improved hinge which is simple and durable in construction and specially adapted to support heavy doors, &c., and arranged in such a manner as to facilitate the hanging of the door and at the same time making the door self-closing.

The invention consists of certain parts and details, and combinations of the same, as will be hereinafter fully described, and then pointed out in the claims.

Reference is to be had to the accompanying drawings, forming a part of this specification, in which similar letters of reference indicate corresponding parts in all the views.

Figure 1 is a side elevation of the improvement as applied to a door. Fig. 2 is an enlarged sectional side elevation of the lower hinge. Fig. 3 is a sectional plan view of the same. Fig. 4 is an enlarged front view of the same. Fig. 5 is a transverse section of the same. Fig. 6 is an enlarged front view of the upper hinge with parts broken out. Fig. 7 is a transverse section of the same. Fig. 8 is a plan view of the same with parts removed. Fig. 9 is a side elevation of a modified form of cam-ring and pivot in closed position, and Fig. 10 is a like view of the same as open.

The door or other similar article A is hung to the door casing or frame B by a lower and an upper hinge C and D, respectively, of which the lower hinge C is partly attached to the door A and partly to the door-sill E, and the upper hinge D is partly secured to the door and partly to the cross-bar F of the casing B. The two hinges C and D are substantially the same in construction, the only difference being in the manner of attaching the same to the sill E and the cross-bar F.

The lower hinge C is provided with a transversely-extending base or bed plate G, formed in its top with a longitudinally-extending groove G', into which is fitted the square part H' of the pivot H, adapted to pass into a casing I, secured to the door A. The pivot H stands vertically in the lower corner of the door, and is securely held in place on the base-plate G by being provided at its bottom with

a square flange H², fitting into a correspondingly-shaped groove G², formed in the plate G at its sides, as is plainly illustrated in the drawings.

The part of the pivot H above the bed-plate G and extending into the casing I is round, the top being formed into a cam H³, on which fits a correspondingly-shaped cam J', formed on the under side of the ring J, also fitted into the casing I, and provided on one side with a lug J², fitting into a vertically-extending groove I', formed in the inside of the circular casing I. A spring K presses on top of this cam-ring J, and on top of the spring rests a cap L, screwing in the upper end of the casing I and serving to hold the spring in place, and at the same time to regulate the tension of the latter by screwing the said cap farther into or out of the casing I. For this purpose the periphery of the cap L is provided with apertures which can be regulated from the outside through an opening I³ in the casing I. The latter is attached to the door A by being provided with front and rear flanges I², adapted to be bolted to the faces of the door.

The adjoining cam ends of the ring J and the pivot H may be made double, as shown in Figs. 9 and 10, so that when the door is swung into an open right-angular position the highest point of the cam on the pivot is engaged by the highest point of the cam on the ring, as shown in Fig. 10. A slight notch is formed at the highest cam-point of the ring and is adapted to be engaged by the highest point of the pivot, so as to lock the door in an open position. A slight pressure on the open door disengages the notch from the lug and the door swings shut by the force of the springs.

A plate N is screwed to the under side of the door, and is also screwed to the under side of the casing I, the round part of the pivot H passing through a suitable aperture in the said plate N. The rear squared end of the pivot H abuts against a short transverse plate O, secured by screws to the base G, as is plainly shown in Fig. 5. The front of the squared part of the pivot H is engaged by a transversely-extending plate P, fitted into the groove G' of the base G and secured to the said base by screws after the door is hung, as hereinafter more fully described.

The upper hinge D is similar in construc-

tion to the lower hinge C, the casing I being secured to the upper corner of the door and its pivot H extending downward in line with the pivot of the lower hinge C. The square 5 upper end of the pivot H abuts against a plate Q, secured to the under side of the cross-bar F, as shown in Fig. 7. Three sides of the square part H' of the pivot H fit into a recess R', formed in the casing R, provided 10 with an upwardly-extending flange R², screwed to one side of the cross-bar F of the door-casing B. The casing R is also provided with a longitudinally-extending plate R³, screwing to the under side of the said cross-bar, and the front square part of the pivot H is engaged by a separate plate R⁴, adapted 15 to be fastened to the casing R, and also by screws to the front of the cross-bar F of the door-casing B. It is understood that the 20 square part H' of this upper pivot H also has a square flange H², which fits into a correspondingly-shaped recess in the casing R.

The operation is as follows: In order to hang the door or similar article, the bed-plate G 25 is fastened to the sill E, so that the top of the said bed-plate is in line with the top of the sill. The front plate P of the said bed-plate is removed to permit the entrance of the square part of the pivot H when the door is 30 to be hung, and in a similar manner the casing R, fastened to the cross-bar F, has its front plate R⁴ removed to permit the entrance of the square part of the pivot H. The casings I of the lower and upper hinges C and D 35 are secured to the door A, the caps L, the springs K, the rings J, and the pivot-pins H being in their proper places. The operators then take the door and slide the same in place by moving the square parts of the pivot-pins H into the recesses G' and R' of the bed-plate G and the casing R, respectively. 40 When the square parts of the pivot-pins strike the rear of the said bed-plate and casing, then the door is in place, and the operators then fasten the plate P to the bed-plate G and the front plate R⁴ to the casing R. The door is then hung in place. Now it will be seen that when the door is 45 opened the cam-rings J turn with the door around the stationary pivot-pins H as the said cam-rings J engage with their projections J² the recesses I' in the casings I, attached to the door A. When the cam-rings J turn, their cams J', when traveling over the 50 cams H³ of the pivot-pins H, are moved toward each other, so as to compress the springs K, and the moment the operator lets go of the door the compressed springs K exert sufficient pressure on the cam-rings J to cause 55 the latter to travel on the cams H³ of the fixed pivots H, whereby the door swings to a closed position as the cam-rings J are forced to their natural position by the pressure of the said 60 springs.

65 It will be seen that when the door is opened,

as above described, the cam-rings J move toward each other, so that the door does not rise or fall and bind on the casing B, which permits of applying this hinge to all kinds of doors. It will further be seen that the hanging of the door is readily accomplished, as it does not require much skill, it only being necessary to fasten the casings I of the two hinges in the proper place on the door, which can be done in the workshop, and then securing the bed-plate G and the top casing R on the proper place on the door-casing, after which the door is hung, as previously described, by simply sliding the square ends of the pivot-pins into the bed-plate G and the casing R, as above described.

Having thus described my invention, I claim as new and desire to secure by Letters Patent—

1. A hinge comprising a casing or tube having attaching means and closed at one end, a helical spring in the closed end of said casing, a sliding ring resting against said spring and having a cam-shaped opposite face and means to prevent its rotation, and a pivot or pintle entering the open end of said casing and having the face of its inner extremity shaped to correspond with the cam-face of the ring, and means for securing the pivot or pintle to the article to which it is to be applied, substantially as set forth.

2. A hinge comprising a tube or casing having attaching means and a screw-plug closing one of its ends, a helical spring within the closed end of the tube and resting against the inner face of the plug, a sliding ring provided with means to prevent its rotation, resting against said spring, and having its opposite face cam-shaped, and the pivot or pintle entering the open end of the tube or casing, having the face of its inner extremity shaped to correspond with the cam and provided with attaching means, substantially as set forth.

3. In a hinge, the combination, with a pivot-pin having one squared end, of a bed-plate or casing adapted to receive the squared end of the said pivot, and a locking-plate adapted to be secured to the said bed-plate or casing and serving to lock the squared end of the said pivot in place, substantially as shown and described.

4. In a hinge, the combination, with a pivot having a flanged squared end, of a bed-plate or casing having a recess adapted to receive the squared flanged end of the said pivot, and a locking-plate adapted to be secured to the said bed-plate or casing and serving to lock the squared end of the said pivot in place, substantially as shown and described.
